Specification for Design.

Patented Dec. 14, 1920.

Application filed June 21, 1920. Serial No. 390,647. Term of patent 14 years.

To all whom it may concern.

Be it known that I, EPHRAIM S. PEASE, a citizen of the United States, residing at Buffalo, in the county of Erie and State of New York, have invented a new, original, and ornamental Design for a Glass Knife, of which the following is a specification, reference being had to the accompanying drawing, forming a part thereof.

In the accompanying drawings:

Figure 1 is a side view of a glass knife showing the design.

Fig. 2 is an edge view thereof showing the cutting edge thereof.

Fig. 3 is a top plan view thereof.

A represents the blade and B the handle of a knife, both blade and handle being made of glass.

I claim—

The ornamental design of a glass knife as shown and described.

EPHRAIM S. PEASE.
